UNITED STATES PATENT OFFICE.

GULIAN V. P. LANSING, OF CHICAGO, ILLINOIS, ASSIGNOR TO AERMORE MANUFACTURING COMPANY, OF CHICAGO, ILLINOIS, A CORPORATION OF ILLINOIS.

DESIGN FOR AN AUTOMOBILE-HORN.

43,081.

Specification for Design.

Patented Oct. 1, 1912.

Application filed July 29, 1912. Serial No. 712,198. Term of patent 7 years.

To all whom it may concern:

Be it known that I, GULIAN V. P. LANSING, a citizen of the United States, residing at Chicago, in the county of Cook and State of Illinois, have invented a new, original, and ornamental Design for Automobile-Horns, of which the following is a full, clear, and exact description, reference being had to the accompanying drawings, forming a part hereof.

My design relates to warning horns or signals for use in connection with automobiles, motor-cycles and similar vehicles, to be attached to the exhaust of the engine thereof and operated by the pressure of the expelled gases, and has for its object to provide a contrivance of this character that is neat and artistic in appearance, as well as compact and convenient.

In the drawings: Figure 1 is a longitudinal elevation of my ornamental design for an automobile horn or the like. Fig. 2 is an end view thereof. Fig. 3 is an end view taken opposite to Fig. 2.

Referring to the drawings, it will be observed that my design consists primarily in mounting a plurality of hollow resonant tubes around an axis and connecting their open ends to a coupling. These tubes are made of metal and have their outer ends

(those farthest from the coupling) stamped or pressed into an hexagonal shape. The opposite ends of these tubes are round in cross-section and have a small segment thereof cut away to form an opening the outer end of which latter is substantially straight and arranged transverse to the axis of said tubes. The coupler comprises a casting the body portion of which is round and the outer portion is cut hexagonal of larger dimensions than the faces of the tubes. The inner portion of this coupling is flared to each side of its axis and provided with a number of ribs corresponding in number to the resonant tubes. These ribs are hollow and have flattened discharge ports in their ends that enter their respective tubes a short distance. Between these ribs the metal is depressed, substantially as shown.

What I claim is:

The ornamental design for an automobile horn, as shown and described.

In witness whereof I have hereunto set my hand and set my seal this 28th day of June, 1912.

GULIAN V. P. LANSING. [L. S.]
